CORE TAKING TOOL

John H. Howard, Whittier, and Alfred C. Catland,
Alhambra, Calif.; said Catland assignor to
Globe Oil Tools Company, Los Nietos, Calif., a
corporation of California

Application February 27, 1937, Serial No. 128,194

8 Claims. (Cl. 255—72)

This invention relates to well drilling tools and relates more particularly to a sample taking tool or core drill for use in the rotary method of well drilling. A general object of this invention is to provide a practical, dependable and improved core drill having a retrievable core barrel.

Another object of this invention is to provide a rotary core taking tool of the character mentioned embodying simple and very effective means for holding the core receiving barrel down and in place in the drill.

Another object of this invention is to provide a core taking tool of the character mentioned in which the hold-down means for holding the core barrel in position is automatically latched or made operative when the barrel is dropped into the drill.

Another object of this invention is to provide a drill of the character mentioned in which the hold-down mechanism may be released by an overshot or retrieving tool when the said tool passes over the barrel to grip the same for removal from the drill.

A further object of this invention is to provide a core taking well tool of the character mentioned that is simple and inexpensive to manufacture and that is easy and convenient to operate and control.

The various objects and features of our invention will be fully understood from the following detailed description of a typical preferred form and application of the invention, throughout which description reference is made to the accompanying drawings, in which:

Fig. 1 is a central longitudinal detailed sectional view of the drill provided by this invention showing the barrel in elevation and illustrating the retrieving tool passing downwardly over the barrel. Fig. 2 is an enlarged longitudinal detailed sectional view of the upper portion of the retrieving tool and the upper portion of the core barrel. Fig. 3 is an enlarged fragmentary vertical sectional view of the lower portion of the drill illustrating the hold-down mechanism. Fig. 4 is a transverse detailed sectional view of the core barrel and the hold-down mechanism taken substantially as indicated by line 4—4 on Fig. 3. Fig. 5 is a transverse detailed sectional view taken as indicated by line 5—5 on Fig. 2. Fig. 6 is a fragmentary longitudinal detailed sectional view of the drill showing the hold-down mechanism released and the retrieving tool in lifting engagement with the barrel and Figs. 7 and 8 are transverse detailed sectional views

taken as indicated by lines 7—7 and 8—8, respectively, on Fig. 6.

The core taking tool of the present invention includes, generally, a core drill 10, a core receiving barrel 11 adapted to be dropped or lowered into the drill 10 to receive the core cut thereby, releasable latch means 12 for holding the barrel 11 in the drill 10 and a tool 13 for releasing the means 12 and for withdrawing the barrel 11 from the drill 10.

The drill 10 is operable to form an annular cut in the earth formation to leave a core and is formed to receive the core receiving barrel 11. The drill 10 includes a drill collar 14 which is an elongate tubular member having heavy or thick walls. The upper end of the drill collar 14 is adapted to be connected with the lower end of a string S of rotary drill pipe. In the case illustrated the drill collar 14 is connected with the string S by a tool joint section 15. A tubular 20 sub 16 is threadedly connected with the lower end of the drill collar 14 and is provided at its lower end with a tapered threaded pin 17. In accordance with the invention an annular recess or socket 18 is provided in the lower end portion 25 of the tubular sub 16. The upper wall of the socket 18 is flat and horizontal to constitute a downwardly facing shoulder 19.

The drill 10 further includes a drill head 20 threaded on the pin 17 of the sub 16. The head 30 20 is tubular having a central vertical opening 21 adapted to receive or pass the core. An annular recess 22 is provided in the upper portion of the head 20 and is co-axial with the opening 21. The recess 22 has cylindrical side walls and 35 a flat upwardly facing bottom wall. Suitable cutting means is provided on the drill head 20 for making an annular cut in the earth formation. In the particular structure illustrated the head 20 has outer roller cutters 23 carried by pins 24 40 through suitable anti-friction bearings and inner roller cutters 25 rotatably carried by pins 26 through similar bearings. The outer cutters 23 are operable to cut the well bore to gauge while the inner roller cutters 25 are operable to trim 45 or shape the core for passage through the opening 21. Ports 27 are provided in the cutter head 20 and receive the circulation fluid from the sub 16 and discharge it downwardly against the cutters 23 and 25.

The barrel 11 is provided to receive and trap the core and in accordance with the invention may be dropped through the string S from the ground surface to seat in the drill 10 where it may receive the core. The barrel 11 is an elong- 55

gate hollow or tubular structure adapted to extend through the sub 16 and the drill collar 14 when in the operative position in the drill. The core receiving barrel 11 is proportioned to extend through the sub 16 and the drill collar 14 with substantial clearance to leave an annular fluid passage 28 for conducting the circulation fluid downwardly to the ports 27.

The lower end portion of the barrel 11 is formed to carry the means 12 and to seat in the bit head or cutter head 20. In the preferred construction illustrated a tubular member 29 is secured to the lower end of the barrel 11 proper and a second tubular member 30 is threaded onto the member 29. The threaded connection between the members 29 and 30 is such that the peripheries of the members are flush. In practice the upper member 29 may be welded on the lower end part of the inner barrel 11. The lower member 30 has an annular internal recess 31 and the lower end of the member 29 forms the upper wall of the recess 31. The lower member 30 of the barrel 11 is proportioned to fit downwardly in the recess 22 of the head 20 and its lower end is flat to seat on the bottom wall of the recess to support the barrel 11 in the head 20. The member 30 cooperates with the recess 22 to center the barrel 11 in the drill and to stabilize the barrel when the tool is in operation. The upper portion of the recess 22 may be flared to guide the member 30 into the recess when the barrel 11 is dropped into the drill. It is to be understood that the lower end of the barrel 11 is open to receive the core from the opening 21. The tubular member 30 fitting the socket 22 prevents the circulation fluid from washing downwardly around the core.

A valve is provided on the upper end of the barrel 11 to prevent the circulation fluid from washing downwardly into the barrel and to allow the fluid trapped in the barrel 11 to escape. The valve on the inner barrel 11 may include a body 33 threaded into the upper end of the barrel 11. A bore or opening 34 extends upwardly into the valve body 33 and has its lower end in communication with the barrel 11. Lateral ports 35 are provided in the body 33 to place the opening 34 in communication with the interior of the drill collar 14. A tubular valve seat 36 is threaded in the opening 34 and is locked in place by a transverse bar 37 cooperating with a notch 38 in its lower end. A ball 39 is arranged in the upper portion of the opening 34 and is adapted to seal downwardly against the seat 36. When the ball 39 is in cooperation with the seat 36 it prevents the downwardly flowing circulation fluid from entering the barrel 11. The ball 39 may be unseated by the fluid trapped in the barrel 11 when the said fluid is displaced from the barrel by the entering core. The valve body 33 is provided with an upwardly projecting stem 40 of reduced diameter. A rounded head 41 is provided on the upper end of the stem 40 and its lower side forms a downwardly facing annular shoulder 42 engageable by the tool 13, as will be hereinafter described.

A core catcher is preferably associated with the barrel 11 to trap or retain the core therein when the barrel is withdrawn from the drill 10 and the well. The core catcher illustrated in the drawings is of simple construction and comprises a ring 43 and core engaging spring fingers 44 attached to the ring. The fingers 44 are riveted or otherwise secured to the interior of the ring 43 and project upwardly and inwardly from the

ring. In accordance with the invention the core catcher ring 43 is arranged in the recess 31 so that the fingers 44 project upwardly and inwardly through the member 29. The ring 43 may be free to turn in the recess 31 or remain non-rotatable in the recess during the drilling operation. The interior of the ring 43 is preferably flush with the interiors of the members 29 and 30 and the wall of the opening 21. The upper ends of the spring fingers 44 are pointed or bevelled to bite into the core when the drill 10 or the barrel 11 is raised.

The means 12 is operable to automatically latch the barrel 11 in the drill 10 to prevent or limit the upward movement of the barrel in the drill. In accordance with the invention the latch means 12 is releasable to be released by the tool 13 for withdrawing the barrel 11 from the drill 10. In the preferred construction the means 12 is carried by the barrel member 29 and includes circumferentially spaced pairs of leaf springs 45 secured to the exterior of the member 29 by rivets or the like. The pairs of springs 45 project upwardly and outwardly from the member 29. A horizontal or transverse segment 46 extends between and connects the upper end portions of each pair of springs 45. The segments 46 are preferably secured to the inner sides of the springs 45 and are curved to be substantially concentric with the longitudinal axis of the barrel 11. The segments 46 may be secured to the springs 45 by rivets 47. The springs 45 and the segments 46 are located to be within the socket 18 when the barrel member 30 is seated in the recess 22. When the barrel 11 is in its operative position in the drill 10 the upper ends of the segments 46 are below and adjacent the shoulder 19. In practice the upper ends of the segments 46 may have suitable clearance with the shoulder 19 when the barrel 11 is seated in the drill 10. During passage of the barrel 11 into or through the drill 10 the springs 45 yieldingly bear outwardly against the interior of the joint section 15, the drill collar 14 and the sub 16 and upon passing the shoulder 19 the springs 45 flex outwardly to positions such as illustrated in Figs. 1 and 3. This brings the segments 46 in latching relation to the shoulder 19 where they oppose the shoulder to prevent or limit upward movement of the barrel 11 in the drill 10.

The automatic latch means 12 further includes parts on the segments 46 to facilitate their release or retraction by the tool 13. These parts may be in the nature of leaf springs 48 projecting upwardly from the segments 46. There may be two springs 48 secured to each segment 46. The springs 48 may be secured to the inner sides of the segments 46 and may be attached to the segments by the rivets 47. The springs 48 extend upwardly some distance from the springs 45 and then curve upwardly and inwardly to bear against the exterior of the barrel 11. Longitudinal grooves 49 are provided in the barrel 10 to partially receive the upper end portions of the springs 48. The grooves 49 serve to maintain the springs 48 in substantially vertical positions. When the barrel 11 is seated in the drill 10 the springs 48 yieldingly bear outwardly against the interior of the sub 16 adjacent the socket 18 and their upper portions bear inwardly against the walls of the grooves 49.

The tool 13 is operable to release the latch means 12 and to grip or engage the barrel 11 for removal from the drill 10 and the well. The tool 13 is in the nature of an overshot adapted to be

operated by a wire line or cable 50. The retrieving tool 13 includes a body 51 having a rope socket 52 on its upper end for connecting it with the cable 50. A vertical opening 53 extends into the body 51 from its lower end and vertically spaced series of ports 54 are provided in the wall of the body 51 to communicate with the opening 53 and permit a free circulation of fluid through the tool 13. In accordance with the invention a sleeve 55 is provided on the body 51 to pass downwardly over the barrel 10 when the tool 13 moves into the drill 10. The sleeve 55 may be welded on the lower portion of the body 51 and has relatively thin walls to pass downwardly through the circulation passage 28 with suitable clearance. The sleeve 55 is of substantial length to cooperate with the means 12 as will be hereinafter described.

The tool 13 includes members or parts for latching under the shoulder 42 for the purpose of removing the barrel 10 when the cable 50 is drawn upwardly. Lifting dogs or latching dogs 56 are pivoted in the opening 53 of the tool body 51. The dogs 56 are segmental or curved in horizontal cross section and are pivotally supported on rivets 57 loosely fitting openings 58 in the dogs. The dogs 56 project upwardly from the rivets 57 and their upper ends are flat and horizontal. Depending tails 59 may be provided on the dogs 56. Spring means are provided to pivot or urge the upper ends of the dogs 56 inwardly so that they may latch under the shoulder 42 when the tool 13 is lowered downwardly over the barrel 11. Leaf springs 60 are secured to the upper end parts of the dogs 56 and bear against the wall of the opening 53 to urge the upper portions of the dogs inwardly toward the longitudinal axis of the tool 13.

The dogs 56 and the lower end of the sleeve 55 are related so that the lower end of the sleeve cooperates with the springs 48 to retract or unlatch the segments 45 before or at the same time that the dogs 56 snap or latch under the shoulder 42. Thus the tool 13 is operable to release the latch means 12 and at the same time grip or have latching cooperation with the shoulder 42 for the purpose of withdrawing the barrel 11 from the drill 10 when the cable 50 is drawn upwardly.

In the operation of the improved core taking tool the drill 10 may be operated in the well on the string S in the usual manner. The cutters 23 and 25 of the drill 10 are operable to drill into the formation and circulation fluid may be pumped downwardly through the drill to flush the cutters and carry away the cuttings. When it is desired to obtain a sample or core of the earth formation the barrel 11 is lowered or dropped through the drilling string S to seat in the drill 10. As described above, the lower member 30 of the barrel 11 is adapted to enter the recess 22 in the cutter head 20 and seat downwardly against its lower wall to support the barrel 11 in the drill. The member 30 may seat in the recess 22 in such a manner that the barrel 11 may rotate with the drill or may remain stationary with the core during the coring or drilling operation. When the barrel 11 is dropped through the drill 10 the springs 45 yieldingly bear against the interior of the drill until the upper ends of the segments 46 pass the shoulder 19, whereupon the springs flex outwardly to bring the segments into latching relation with the shoulder. With the segments 46 in this position they may cooperate with the shoulder 19 to hold the barrel 11 against upward movement or limit the upward movement of the barrel. Thus the barrel 11 is automatically

latched in its proper position in the drill 10. The drilling operation may then be resumed. The circulation fluid pumped downwardly through the string flows through the passage 28 around the barrel 11 and discharges through the ports 21. The core cut or formed by the cutters 23 and 25 is received in the opening 21 and the barrel 11. The core catcher ring 43 may remain non-rotatable or stationary due to the engagement of the spring fingers 44 with the core.

The coring operation may continue until a core of sufficient length has been received in the barrel 11. The drilling operation may then be suspended and the cable 50 carrying the tool 13 is run into the string S. When the tool 13 enters the drill 10 its sleeve 55 passes downwardly over the barrel 11 and when the lower end of the sleeve approaches the springs 48 the dogs 56 move downwardly over the head 41. The lower end of the sleeve 55 cooperates with the inwardly curved parts of the springs 48 to flex the springs 45 inwardly and thus move the segments 46 inwardly toward or against the barrel 10. When the sleeve 55 is cooperating with the springs 48 the dogs 56 are passing downwardly over the head 41 and the engagement of the head with the dogs may pivot or swing the dogs outwardly. When the upper ends of the dogs 56 pass downwardly over the head 41 the dogs spring inwardly under the action of the springs 60 so that their upper ends are latched under the shoulder 42. Thus the latch means 12 is released and the dogs 56 are latched under the shoulder 42.

The wire line or cable 50 is then pulled upwardly to withdraw the barrel 11 from the well. The dogs 56 cooperating with the shoulder 42 transmit the upward movement to the barrel 11 so that the barrel is drawn upwardly with the line or cable 50. When the barrel is pulled upwardly the core catcher springs 44 grip or bite into the core to break it loose from the formation and to retain it in the barrel 11. The barrel 11 carrying the core is drawn upwardly through the string S on the line 50 to the surface of the ground. Following the withdrawal of the barrel 11 the drilling operation may be resumed or, if desired, another core may be obtained by dropping or lowering the emptied barrel 11 or a second similar barrel 11 through the string S and the above operation may be repeated.

Having described only a typical preferred form and application of our invention, we do not wish to be limited or restricted to the specific details herein set forth, but wish to reserve to ourselves any variations or modifications that may appear to those skilled in the art or fall within the scope of the following claims.

Having described our invention, we claim:

1. A core taking tool of the character described including, a tubular drill, a cutting head on the drill operable to form a core and having a seat, the drill having an internal shoulder adjacent the head, a barrel adapted to be dropped into the drill to rest on the seat to be in position to receive the core, spring latches on the lower part of the barrel for engaging under the shoulder to releasably retain the barrel in the drill, and upwardly projecting parts on the latches to be engaged by a tool run into the drill to effect the release of the latches from the shoulder.

2. A core taking tool of the character described including, a tubular drill operable to form a core, the drill having an internal shoulder, a barrel adapted to be dropped into the drill to receive the core, spring arms projecting upwardly and out-

- wardly from the barrel, latch members carried by the arms for cooperating with the shoulder to latch the barrel in the drill, and parts projecting upwardly from the latch members adapted to be engaged by a tool run into the drill to effect the release of the latch members from the shoulder.
3. A core taking tool of the character described including, a tubular drill operable to form a core, the drill having an internal shoulder and an internal seat below the shoulder, a barrel adapted to be dropped into the drill to rest on the seat to receive the core, a core catcher in the lower portion of the barrel, and latch means on the barrel adjacent its lower end for cooperating with the shoulder to releasably retain the barrel in the drill, the latch means including upwardly and inwardly projecting parts adapted to be engaged by a tool run into the drill to effect the release of the latch means.
4. A core taking tool including, a tubular body to be connected with a tubular well drilling string, the body having an internal shoulder adjacent its lower end, a tubular cutting head on the lower end of the body, a barrel adapted to be passed through the string, a tubular assembly secured to the lower end of the barrel and adapted to seat in the head, a core catcher carried in said assembly, a latch carried by said assembly engageable under said shoulder to releasably retain the barrel in position to receive the core, and an upwardly and inwardly projecting part on the latch engageable by a tool run down over the barrel to effect the retraction of the latch from said shoulder.
5. A core taking tool including, a tubular body to be connected with a tubular well drilling string, the body having an internal shoulder adjacent its lower end, a tubular cutting head on the lower end of the body, a barrel adapted to be passed through the string, a tubular fitting on the lower end of the barrel for seating in the head, spring arms projecting upwardly and outwardly from the fitting, members on the arms adapted to cooperate with the shoulder to retain the barrel in position to receive the core, and parts on the members engageable by a retrieving tool to move the members out of latching relation to the shoulder.
6. A core taking tool including, a tubular body to be connected with a tubular well drilling string, the body having an internal shoulder adjacent its lower end, a tubular cutting head on the lower end of the body, a barrel adapted to be passed through the string, a tubular assembly secured to the lower end of the barrel and adapted to rotatably seat in the head, a latch carried by said assembly for engaging under the shoulder to releasably retain the barrel in position to receive the core, and a part on the latch engageable by a tool passed down over the barrel to effect the release of the latch.
7. A core taking tool including, a tubular body to be connected with a tubular well drilling string, the body having an internal shoulder adjacent its lower end, a tubular cutting head on the lower end of the body, a barrel adapted to be passed through the string, a tubular fitting on the lower end of the barrel for seating in the head, spring arms projecting upwardly and outwardly from the fitting, members on the arms adapted to cooperate with the shoulder to retain the barrel in position to receive the core, and upwardly and inwardly projecting parts on the members engageable by a retrieving tool to move the members out of latching relation to the shoulder, the barrel having grooves receiving the upper portions of said parts.
8. A well core drill comprising a tubular body provided at its lower end with a tubular cutting head, an abrupt internal downwardly facing shoulder on the body adjacent the head, a core receiving barrel adapted to be lowered into the body to seat in the head, the barrel entering the body with substantial clearance and leaving an annular clearance space therein for receiving a tubular tool, spring arms projecting upwardly and outwardly from the lower portion of the barrel and having abrupt upper ends engageable with the said shoulder to latch the barrel in the body, and parts attached to the inner sides of the arms and projecting upwardly and inwardly therefrom into said space to be engageable by said tool to effect the release of the arms from the shoulder.

JOHN H. HOWARD.
ALFRED C. CATLAND.
